DUMP BODY FOR SMALL TRUCK

Roy F. Broyhill, Dakota City, Nebr. 68731

Filed Feb. 14, 1972, Ser. No. 226,394

Term of patent 14 years

Int. Cl. D12—08

U.S. Cl. D12—15

FIG. 2

FIG. 3

FIG. 4FIG. 5FIG. 1 is a rear perspective view of a dump body for small truck showing my new design, it being understood that the broken lines are for illustrative purposes only.

FIG. 2 is a side elevational view thereof opposite to the side shown in FIG. 1,

FIG. 3 is a front elevational view thereof,

FIG. 4 is a top plan view thereof, and

FIG. 5 is a bottom plan view thereof.

I claim:

The ornamental design for a dump body for small truck, as shown and described.
